UNITED STATES PATENT OFFICE.

CLARENCE A. FULLERTON, OF NEW YORK, N. Y.

GLASS PASS-BASKET.

1,264,051.

Specification of Letters Patent. Patented Apr. 23, 1918.

Application filed June 28, 1916. Serial No. 106,515.

To all whom it may concern:

Be it known that I, CLARENCE A. FULLERTON, a citizen of the United States, residing at New York, in the county of New York and State of New York, have invented certain new and useful Improvements in Glass Pass-Baskets; and I do hereby declare the following to be a full, clear, and exact description of the invention, such as will enable others skilled in the art to which it appertains to make and use the same.

This invention relates to receptacles for use in the walls of partitions between the booths or cages of tellers in banks and for convenience sake may be termed a pass basket.

It has for an object to provide a device of this character which may be made of glass or other vitreous materials and which may be securely held in the wall of a cage.

Further objects will be apparent from the following specification, appended claims and drawing, in which,

Figure 1 is an isometric view showing the device in place, and

Fig. 2 is a cross sectional view through the wall of the cage showing how the basket is held in place.

This invention provides for the formation of a receptacle of glass or other suitable material, which may be held in the wall of a bank teller's cage by the meeting edges of sections of grille work which constitutes said wall and said basket will be shaped to properly receive articles which need to be passed from one cage to another, while at the same time affording protection to said articles against accidental displacement.

Referring to the drawings, in which the device is clearly shown, 10 and 11 indicate sections of grille work which are provided with the binding strips 12 and 13 to permit said sections of grille work being held together in the ordinary manner. The binding strip of the section 10 is bent as at 14 to form a passage way between said binding strips for a limited portion of their length,

and to the under face of the section 15 of the strip 12 is attached a rounded or otherwise shaped section 16 to present a smooth under surface for the section 15 as articles are being passed through the opening thus formed.

A glass or other receptacle 17 is placed in the opening and this receptacle has a bead 18 formed thereabout from the opposite ends of which continues the curved bottom 19. The side walls are recessed as at 20 to receive the rounded strip 16 and the bottom of this receptacle is provided with the parallel ribs 21 between which the strip 13 passes. It will be seen that when the parts are assembled and the receptacle is included in the opening so formed by the offsets 14 and section 15, this receptacle is securely held between the sections of the grille work by the recesses 20 and the ribs 21 and that no further fastening means are required.

It is also apparent that modification may be made in view of the foregoing, as it is possible to alter the relative positions of the ribs and recessed portions to meet existing conditions but in each event the principle will remain.

Having thus described this invention, I claim:—

1. A pass basket for partitions comprising a hollow receptacle, having the central portions of the side walls along the upper edges thereof notched, a groove formed across the bottom face of said receptacle under said notched portions, said groove and said notched portions of said receptacle comprising a central portion of reduced cross sectional dimension, and said receptacle being secured in a partition by having said reduced portion gripped between meeting edges of sections of a partition.

2. A pass basket for partitions comprising a vitreous dished receptacle having the bottom rounded generally from end to end, side walls rising above said curved bottom, said side walls having their upper edges notched centrally therein, said receptacle having enlargements formed in spaced relation across the central portion of the under face of the bottom, and meeting edges of sections of partitions shaped to grip and bind between the enlargements formed on the upper edges of the side walls and across the under face of the bottom between said enlargements.

In testimony whereof I affix my signature in presence of two witnesses.

CLARENCE A. FULLERTON.

Witnesses:

Jos. R. GARLAND,

WILLIAM E. CORCORAN.
